DUAL PNEUMATIC POWER CONTROL

Roy R. Stevens, Forest Hills, Pa., assignor to The
Westinghouse Air Brake Company, Wilmerding,
Pa., a corporation of Pennsylvania

Application February 28, 1942, Serial No. 432,776

24 Claims. (Cl. 192—01)

1

This invention relates to means for controlling the positioning and/or operation of devices such as engine throttles, clutches, boat rudders, power reverse gear, or engine starters, and more particularly to manually controlled pneumatic power arrangements for such use.

One object of the invention is the provision of an improved arrangement for controlling one or more devices of the above type.

Another object of the invention is the provision of such an arrangement which is relatively quick or fast and positive in operation.

Another object of the invention is the provision of an improved arrangement of the above type particularly adapted for remote manual control.

In certain types of marine service employing Diesel engines for propelling the craft and clutches for connecting and disconnecting the engines to and from the propeller, it is essential that the engine controlling means be not only relatively fast and positive in operation but also capable of remote control from the engine room adjacent the engine as well as from the bridge or pilot house of the craft so that if for any reason the control means on the bridge fails, the engineer in the engine room may take over the control of the craft.

Another object of the invention is therefore the provision of a remote pneumatic control system for such use adapted to be controlled from either the bridge or engine room and embodying means for selectively determining the control station.

Another object of the invention is the provision of such a system embodying means for rendering one station ineffective when desired or upon failure thereof and for rendering the other station effective to control the operation of the craft.

Other objects and advantages will be apparent from the following more detailed description of the invention.

An illustrative embodiment of the invention is shown in the accompanying drawings in which:

Figs. 1—1A, when arranged side by side with Fig. 1 at the left-hand, is a diagrammatic view, partly in section and partly in outline, of an engine clutch, throttle and starter control system for a Diesel engine driven marine craft; Fig. 2 is a sectional view taken longitudinally through the clutch shifting engine or motor and certain control means therefor shown in outline in Fig. 1A; Fig. 3 is a diagrammatic view of a selector valve shown in Fig. 1 but in a different control position; Fig. 4 is a diagrammatic view, partly in

section and partly in outline, of a modification of the structure shown in Fig. 1; and Fig. 5 is a sectional view of a modified form of a portion of the invention.

5

General description

In Figs. 1—1A the reference numeral 1 indicates a Diesel engine of the type adapted to be started by compressed air supplied through a starter pipe 2 by means to be hereinafter described. The engine 1 is adapted to be connected through a clutch 3 and a transmission 4 to a propeller shaft 5 for operating said shaft to turn a propeller (not shown) for driving the craft.

15 The clutch 3 may be of the well known twin disk type having a forward position and a reverse position for determining the direction of rotation of shaft 5 and thereby the direction of movement of the craft, and an intermediate or neutral position for disconnecting the engine from the shaft. In clutches of this type toggles and springs are often used to hold the clutch in one or another of its positions, the toggles having to be overcome for moving the clutch out of its different positions. A lever 6 secured to a clutch 20 operating shaft 7 is provided for rocking the shaft to move the clutch to its different positions, this lever having forward, neutral, and reverse positions indicated by legends on the drawings and 25 corresponding to the positions of the clutch.

The reference numeral 10 indicates a fuel supply device for the engine 1. This device is adjustable by an arm 11 for varying the amount of fuel supplied to and thereby the speed and/or power of the engine. The arm 11 has an engine idling position in which it is shown and is adapted to be moved to and occupy any selected position between idling and a position designated on the drawing as full speed to obtain maximum engine 30 speed or output of power.

35 The invention resides in the means for positioning the clutch lever 6 and the arm 11 of the fuel supply device, and the arrangement for selectively controlling said means and the starting 40 of the engine 1 pneumatically and remotely from any one of a plurality of control stations. For this reason and also due to the fact that the parts shown in the drawing and above described are so well known a further showing and description 45 thereof are not deemed essential herein to a clear and comprehensive understanding of the invention and have therefore been omitted.

Control arrangements for clutch 3

50 A reversing engine or fluid operated motor 14

constructed in accordance with the invention, is secured to and carried by the transmission 4 for selectively positioning the clutch 3.

This engine or motor comprises a clutch control power cylinder 15 containing a double acting piston 16 having at one side a pressure chamber 17 connected to a pipe 18 and having at the opposite side a pressure chamber 19 connected to a pipe 20.

The piston 16 comprises a central head portion 21 and two oppositely arranged followers 22 and 23 clamped against the opposite faces of said head portion between a shoulder 24 provided on a piston rod 25 and a nut 26 provided on one end of said rod. Clamped between the follower 23 and head 21 is an inwardly extending portion 27 of a packing cup 28 which has a sealing or skirt portion 29 extending from the outer edge of the portion 27 in the direction of pressure chamber 17. The skirt portion 29 of the packing cup is generally cylindrical in shape to engage the interior wall of cylinder 15 for preventing the passage of fluid under pressure or compressed air in the direction from chamber 17 to chamber 19, it being noted that pressure of fluid in chamber 17 acting on the interior surface of the skirt portion 29 is adapted to force same into sealing contact with the wall of the power cylinder. An oppositely disposed packing cup 28a of the same construction as cup 28 is clamped between the piston head 21 and follower 22 with its skirt portion 29a extending in the direction of chamber 19 and also arranged to engage and to be forced into sealing contact with the wall of cylinder 15 by fluid pressure supplied chamber 18, for preventing the passage of such fluid to chamber 17.

The end of pressure chamber 19 is closed by a pressure head 30 to which the pipe 20 is connected and which is provided centrally with a suitable bearing through which the piston rod 25 extends. A suitable packing 31 secured to the pressure head 30 engages the periphery of the piston rod 25 for preventing leakage of fluid under pressure from chamber 19 to the atmosphere along said rod.

The outer end of the piston rod 25 is connected by screw threaded engagement with one end of a member 32 the opposite end of which is connected by a pin 33 to the adjacent end of a link 34. The other end of the link 34 is provided with a screw threaded bore to adjustably receive the threaded end of an eye bolt 35, the eye end of which is connected by a bolt 36 to the clutch operating and positioning lever 6. The clutch lever 6 is thus connected to piston 16 for movement thereby and is adapted to occupy the neutral position shown for disconnecting the engine 1 from the power shaft 5 when said piston occupies a neutral position substantially intermediate the ends of the power cylinder 15, as shown in the drawing. Movement of the piston 16 under the action of fluid pressure, as will be later described, in the direction of the left-hand as viewed in Fig. 2 is adapted to move the lever 6 and thereby the clutch to the forward position for connecting the engine 1 with the propeller shaft 5 to propel the craft in a forward direction. Movement of the piston 16 in the opposite direction will operate the lever 6 and thereby the clutch to reverse position for causing the craft to be moved in reverse, as will be readily seen.

With the clutch in forward position it is undesirable for the clutch shifting bearings (not

shown) to remain under pressure from the piston 16 since rapid wear of such bearings would occur. The same is generally true of clutch shifting bearings placed under load when the clutch is moved to reverse position, but in certain cases where the reverse position of the clutch is little used, such loading is not considered particularly objectionable. The follower 22 is therefore provided with a stop rib 37 adapted to engage the pressure head 30 in the forward position of the clutch to take the force of fluid pressure on the piston and thus relieve the clutch bearings of such force. For the same purpose a stop rib 38 may also be provided on the follower plate 23 for engagement with the opposite end of the power cylinder 15 when the clutch is in the reverse position. The rib 38 may be omitted however where it is desired that the reverse clutch be held in its fully engaged position by the piston 16.

Extending longitudinally of the clutch control cylinder 15 and rigidly secured thereto by one or more bolts 41 is a bracket 42. One end of this bracket terminates substantially at pressure head 30 and carries a pilot cylinder device 43 while the opposite end overhangs the clutch control cylinder 15 and is provided with a wall 44 for carrying a clutch control valve 45.

The clutch control valve 45 comprises a casing 49 having a mounting face 46 for engaging the wall 44 and for receiving cap screws 47 extending through the wall 44 to rigidly secure said casing to the bracket 42. By applying the cap screws 47 to bores 48 located in wall 44 above the bores in which the cap screws are shown in the drawing, the casing of the clutch control valve 45 may be mounted in a more elevated position with respect to the clutch control cylinder 15, than shown in the drawing. Any desired number of such adjustments of the control valve 45 with respect to the cylinder 15 may be provided, although only one is shown in the illustration.

An operating lever 50 having on one end a ball 51 disposed in a socket provided in casing 49 of the clutch control valve extends through a slot 52 provided in a cover 53 which is secured to the top of casing 49. This slot extends in the direction of the length of the clutch control cylinder 15 and provides for rocking movement of the lever 50 in a like direction, such movement being limited in one direction by engagement of the lever with a wall 54 at one end of the slot and in the opposite direction by engagement with a wall 55 at the opposite end of the slot.

Within the cover 53 the lever 50 has two oppositely disposed arms 56 and 57, the arm 56 being provided for controlling the operation of a self-lapping valve mechanism 58 which is provided for controlling the pressure of fluid in pressure chamber 19 of the clutch control cylinder 15, while the arm 57 is provided for controlling a like self-lapping valve mechanism 59 arranged to control the pressure of fluid in pressure chamber 17.

Both of the self-lapping valve mechanism 58 and 59 may be identical in structure and each may therefore comprise a fluid pressure supply valve 61 contained in a chamber 62 which is constantly supplied with fluid under pressure from a reservoir 63 by way of a pipe 64 which is connected to a cavity 65 in the casing 49 and which cavity is open through a passage 66 to the chamber 62.

The valve 61 is arranged to cooperate with an annular valve seat 67 for controlling communication between chamber 62 and a chamber 68

which in the valve mechanism 58 is connected by pipe 20 to pressure chamber 18 in the clutch control cylinder 15. In the valve mechanism 59 this chamber 68 is connected to pressure chamber 17 by way of pipe 18. A spring 73 in chamber 62 acts on the valve 61 for urging same into sealing contact with the seat rib 67.

In each chamber 68 is a fluid pressure release valve 69 which is connected to the supply valve 61 by a stem 70. Above the exhaust valve 69 is a movable abutment preferably in the form of a piston 74 which is slidably mounted in a bore and which has an annular seat rib on its lower face arranged to cooperate with the release valve 69 for controlling communication between the chamber 68 and a bore 12 extending through the piston and opening to a chamber 75 at the opposite face thereof, the chamber 75 being open to an exhaust passage or pipe 76 leading to the atmosphere. A control spring 77 disposed in chamber 75 bears at one end on piston 74 while the opposite end bears against a plunger 78 which is slidably mounted in the casing. An adjustable set screw 79 in the arm 56 bears against the plunger 78 in the valve mechanism 58 while a like screw 79 bears against the plunger 78 in the valve mechanism 59.

With the operating lever 50 in its normal or neutral position shown each of the screws 79 is adjusted to so position the plungers 78 of the valve mechanism 58 and 59 as to provide certain chosen equal fluid pressures in both chambers 17 and 18 of the power cylinder 15, as will now be explained.

When the plunger 78 of each of the valve mechanisms 58 and 59 is moved or adjusted to the position shown by the set screw 79, it acts initially through the control spring 77 to move the piston 74 into contact with the release valve 69 for closing the exhaust communication from chamber 68 and then acts through said valve to unseat the supply valve 61. Fluid under pressure then flows past the supply valve 61 to chamber 68 and thence through pipe 20 or pipe 18 to the respective pressure chamber 19 or 17. This flow of fluid under pressure continues until the pressure obtained in chamber 68 and acting on the lower face of the piston 74 in each valve mechanism is increased to a degree sufficient to overcome the pressure of the control spring 77 and move said piston in an upwardly direction to permit closure of the supply valve 61 and thus prevent further flow of fluid under pressure to chamber 68 and the connected pressure chamber 19 or 17. Thus the pressure obtained in the pressure chambers 19 and 17 of the power cylinder with the lever 50 in the neutral position shown is limited in accordance with the pressure of the control springs 77 as determined by the adjustment of screws 79, and it is intended that these adjustments will be such as to provide equal degrees of fluid pressure in said chamber under this condition.

In case there is leakage of fluid under pressure from either pressure chamber 17 or 19 in the power cylinder 15, the consequent reduction in pressure in chamber 68 below the control piston 74 of the respective valve mechanism 58 or 59 results in the control spring 77 moving said piston downwardly for unseating the supply valve 61 to again supply fluid to the respective pressure chamber. When the pressure in the pressure chamber is then restored to its original value, such pressure in chamber 68 acting on piston 74 will again move said piston against the control

spring 77 to the position in which the supply valve 61 is unseated. Thus the valve mechanisms 58 and 59 will operate to maintain the pressure in the respective pressure chamber 17 or 19 against leakage at the degree provided for by the adjusted positions of plungers 78.

If the plunger 78 in either valve mechanism 58 or 59 is moved further in a downward direction, as will be later described, the corresponding change in position of the upper end of the control spring 77 will act through piston 74 to unseat the supply valve 61 and permit a further supply of fluid under pressure to the respective chamber 19 or 17 in the control cylinder 15 and this supply will continue until the pressure acting on the piston 74 is increased to a degree sufficient to overcome the opposing increased pressure of control spring 77. The piston 74 will then be moved in an upwardly direction to permit seating of the supply valve 61 and thus again limit the pressure obtained in the pressure chamber 19 or 17 and control chamber 68 to a degree depending upon the position of the plunger 78.

In case the plunger 78 is allowed to move in an upwardly direction the pressure of control spring 77 on the piston 74 will be reduced to a degree below the opposing pressure of fluid in chamber 68 whereupon said fluid pressure will move said piston in an upwardly direction and out of seating engagement with the exhaust valve 69. When this occurs, fluid under pressure will be released from chamber 68 and the respective control chamber 19 or 17 in the power cylinder 15 until such pressure acting on the piston 74 is reduced to a degree slightly below the opposing force of the control spring 77 whereupon said spring will move said piston downwardly into contact with the exhaust valve 69 and prevent further release of fluid under pressure from the respective control chamber 19 or 17. Thus under this condition the pressure of fluid in the power cylinder will also be limited to a degree dependent upon the position of the plunger 78.

From the above description it will now be seen that the pressure of fluid in the pressure chambers 17 and 19 at the opposite sides of the clutch control piston 16 will be varied in accordance with the position of the plunger 78 in the valve mechanisms 58 and 59. The position of these plungers is controlled by the adjusting screws 79 carried by the lever 50 and, as before mentioned, these screws are so adjusted that in the neutral position of the lever 50 the plungers 79 will be positioned to maintain the same chosen degree of pressure, such as fifty pounds per square inch, in both chambers 17 and 19 at the opposite sides of the clutch control piston 16 under which condition said piston will remain in any position which it may occupy within the cylinder 15.

If the lever 50 is rocked from neutral position in a counterclockwise direction it will act to move plunger 78 in the valve mechanism 59 in a downwardly direction for thereby operating said valve mechanism to effect an increase in fluid pressure in pressure chamber 17 of the power cylinder 15. At the same time the adjusting screw 79 in the lever arm 56 will be moved in an upwardly direction to permit corresponding movement of plunger 78 in the valve mechanism 58 to thereby effect operation of said valve mechanism to reduce the pressure in chamber 19 at the opposite side of the clutch control piston 16. A differential of pressures will thereby

be created on the piston 16 acting in the direction of the left-hand for effecting movement of said piston and thereby of the piston rod 25 in the direction of the left-hand.

If the lever 50 is rocked in a clockwise direction from its neutral position the consequent operation of the valve mechanisms 58 and 59 will create a differential of pressures on the piston 16 which will act to move same and the rod 25 in the direction of the right-hand.

The degree of pressure differential obtained on the piston 16 upon operation of the lever 50 from its neutral position shown, as just described, will be varied in accordance with the degree of such movement out of neutral position and the corresponding degree of displacement of the plunger 18 in valve mechanisms 58 and 59 in either an upwardly direction or a downwardly direction, as will be readily seen. A maximum differential on the piston 16 will be obtained by moving the lever 50 into contact with either of the shoulders 54 or 55.

The pilot cylinder device 43 comprises two oppositely disposed cylinders 82 and 83, the adjacent open ends of which are rigidly connected together by one or more screws 84. A gasket 85 is interposed between the ends of the cylinders 82 and 83 to prevent leakage of compressed air from the interior of the cylinders. The cylinder 83 has mounting lugs 86 engaging the bracket 42 and through the medium of which the cylinder device is rigidly secured to said bracket.

Within the cylinder 83 is a double acting piston 87 having at one side a chamber 88 open to a control pipe 89 and having at the opposite side a chamber 90 open to a control pipe 91. A piston rod 92 extending through a suitable bore in the closed end of cylinder 82 and through chamber 90 is connected at one end to the piston 87. A suitable packing 93 is secured to the outer end of the cylinder 82 and bears against the periphery of piston rod 92 for preventing leakage of fluid under pressure from chamber 90 to the atmosphere along said rod.

A pair of spring seats 94 and 95 contained in chamber 90 are slidably mounted on a reduced section 96 of the piston rod 92, the seat 94 having at one end an inturned annular flange 97 arranged to engage an annular shoulder 98 on the piston rod 92 and at the opposite end an out-turned flange 99 arranged to contact the closed end of cylinder 82. One end of the spring seat 95 is arranged to engage the left-hand face of piston 87 while the opposite end is provided with an out-turned flange 100 adapted to engage a shoulder 101 on the cylinder 83.

A coil spring 102 encircling the reduced section 96 of the piston rod bears at one end against the spring seat 94 and at the opposite end against spring seat 95. This spring is under compression and therefore effective to urge the spring seats 94 and 95 apart into contact respectively with shoulder 98 on piston rod 92 and shoulder 101 of the cylinder 83 under which condition the seat 94 will be in contact with the cylinder 82 and seat 95 will be in contact with the piston 87 for defining the neutral position of said piston.

Movement of the piston 87 in the direction of the left-hand will be opposed by the control spring 102 and this movement will be relative to the spring seat 94, it being seen that the seat 95 will under this condition move with the piston. Such movement however is adapted to be limited by engagement of the flange 100 on the spring seat 95 with a ring 103 clamped between the

cylinders 82 and 83. Movement of the piston 87 and rod 92 in the direction of the right-hand will be relative to the seat 95 and opposed by the spring 102 due to the fact that said spring will be compressed by seat 94 which moves with the rod 92 in this direction. Such movement is however adapted to be limited by contact of spring seat 94 with the ring 103. It will thus be seen that movement of piston 87 in either direction will be opposed by spring 102 so that upon supply of fluid under pressure to either chamber 88 or chamber 90 for effecting movement of the piston 87 in one direction or the other, as will be later described the position which the piston 87 will assume will be determined by the pressure of such fluid and the opposing pressure of said spring. It will also be seen that the spring 102 will neutralize the piston 87 when both chambers 88 and 90 are substantially void of fluid under pressure.

The outer end of piston rod 92 is connected by screw threaded contact with one end of a link 104. The opposite end of link 104 is in the form of a jaw within which is disposed an intermediate portion of a lever 105. In this portion of the lever 105 is a slot 106 extending lengthwise of the lever, and slidably mounted in this slot is a crosshead 107. A pin 108 extends through this crosshead and the oppositely arranged jaws of link 104 thereby connecting the piston 87 to the lever 105 and providing for relative movement between the lever and crosshead 107.

The lower end of lever 105 is bifurcated to straddle the link 32 which is secured to the outer end of the power piston rod 25, and is connected to said link by a pin 109. The upper end of lever 105 is connected by a pin 110 to one end of a link 111 the other end of which has an adjustable screw threaded connection with one end of a rod 112. The opposite end of rod 112 has a screw threaded connection with one end of a link 113 the opposite end of which is connected by a pin 114 to the outer end of lever 50 of the control valve device 45.

The pilot cylinder device 43 is adapted to control the operation of the control valve 45 and thereby the power cylinder 15 in accordance with the supply of fluid under pressure to either one of chambers 88 or 90 when the other chamber is vented. The manner in which the pressure of fluid in these chambers is controlled will be hereinafter brought out.

Let it initially be assumed that both chambers 88 and 90 are at atmospheric pressure under which condition the spring 102 will be holding the piston 87 in its neutral position shown. With the piston 87 in its neutral position and the operating lever 50 of the control valve 45 also in its neutral position, both valve mechanisms 58 and 59 will be effective to provide the same degree of fluid pressure in chambers 17 and 18 of the power cylinder 15 and the piston 16 of said cylinder will therefore occupy its neutral position shown, as will be brought out in the description to follow.

Now let it be assumed that with the chamber 90 in the pilot cylinder device 43 at atmospheric pressure, fluid under pressure is supplied to the chamber 88 to a degree which will effect movement of the piston 87 in the direction of the left-hand against the opposing pressure of spring 102. This movement of the piston 87 will act through the rod 92 and crosshead 107 to rock the lever 105 in a counterclockwise direction about pin 109 carried by the power cylinder pis-

ton rod 25. The pin 108 constitutes a fixed fulcrum for lever 105 at this time due to the friction between the packing cups 28 and 28a in the power cylinder and the cylinder wall and also due to the fact that the force required to move the clutch, to which the piston rod 25 is connected is in excess of that required for rocking the lever 50 of the control valve 45.

This counterclockwise rocking of the lever 105 acts through the rod 112 to rock the lever 50 of the control valve 45 in a counterclockwise direction and this operates the valve mechanism 58 to effect an increase in pressure in pressure chamber 17 of the power cylinder 16 and also effects operation of the valve mechanism 59 to cause a corresponding reduction in pressure in pressure chamber 19. A differential of pressures is thus created on the power piston 16 by the increase in pressure on one side and the simultaneous reduction in pressure on the opposite side which acts to move said piston in the direction of the left hand.

As the piston 16 is thus moved toward the left hand, it rocks the lever 105 in a clockwise direction about the crosshead 107 the position of which is fixed by the pressure of fluid in chamber 88 acting on the piston 87, and this rocking of lever 105 moves the rod 112 in the direction of the right hand which effects clockwise rocking of the control valve lever 50. As the control lever 50 is thus rocked, the valve mechanism 59 operates to reduce the pressure of fluid in pressure chamber 17 of the power cylinder and the valve mechanism 58 acts to simultaneously increase the pressure of fluid in pressure chamber 19 and these pressures will become equalized and movement of the piston 16 will as a consequence cease, when the upper end of the lever 105 obtains its normal position shown for neutralizing lever 50 of the control valve 45.

In case the pressure of fluid supplied to chamber 88 is less than required to effect full movement of piston 87 in the direction of the left-hand, an increase in such pressure will change the position of the crosshead 107 and thereby of lever 105 to again cause operation of the control valve 45 to move the piston 16 further in the direction of the left-hand to a new position depending upon the new position of the piston 87. It will thus be seen that the piston 16 may be caused to move to and stop in any desired position to the left of the neutral position shown as determined by the position of the piston 87 in the cylinder 83 which in turn is dependent upon the pressure of fluid supplied through pipe 89 to chamber 88 for acting on the piston 87.

In case the chamber 88 is maintained open to the atmosphere and fluid under pressure is supplied to chamber 80, the piston 87 will be caused to move in the direction of the right-hand to a position dependent upon the pressure of such fluid. The control valve 45 will as a consequence be operated to cause movement of the power cylinder piston 16 in the same direction and to a corresponding position in the same manner as just described for effecting movement in the opposite direction.

It will thus be seen that regardless of the direction of movement of the pilot piston 87 the power cylinder piston 16 will move in a corresponding direction and to a corresponding position as determined by the pressure of fluid supplied to act on either one face or the other of said pilot piston.

Where piston 16 of the power cylinder 15 is

connected to a clutch by lever 6 as shown in Fig. 1A, it will be apparent from the above description that if fluid under pressure is supplied to chamber 88 in the pilot cylinder 43, the piston 16 will be caused to rock the clutch control lever 6 from "Neutral" position in the direction of the "Forward" position and the extent of such movement will depend upon the pressure of fluid supplied to said chamber, whereby the clutch may be moved to its fully engaged position attained at the dash line designated by the legend Forward, or it may be moved to any desired intermediate position to provide for gradual or partial engagement of the clutch. On the other hand, if fluid under pressure is supplied to chamber 80 in the pilot cylinder 43, the power piston 16 will rock the control lever 6 in the direction of "Reverse" position to provide any desired degree of engagement of the reverse clutch.

In use it has been found that the power cylinder piston 16 will accurately position a device, such as a clutch, in accordance with the position of the pilot piston 87, as determined in turn by the pressure of fluid supplied to act on either one face or the other of said piston, and that such positioning will be obtained substantially with, although following, movement of the pilot piston 87 to a selected position.

When it is desired to move the clutch to neutral position, both chambers 88 and 80 in the pilot cylinder device 43 will be vented to permit spring 102 to neutralize the piston 87 for thereby rocking the lever 105 about the pin 108 to actuate lever 50 in the control valve device 45 in either one direction or the other, dependent upon the position of piston 16 in the cylinder 15 at either one side or the other of its neutral position, to create a differential of pressures on said piston for effecting movement thereof back toward neutral position. As the power piston 16 is thus moved toward neutral position, the control valve lever 50 is returned in the direction of its neutral position and attains such position at substantially the time the piston 16 attains its neutral position whereby the pressure of fluid acting on the opposite sides of the power piston 16 will equalize and stop the piston in its neutral position to thereby position the clutch control lever 6 in "Neutral" position.

It is important to note that the differential for moving piston 16 in one direction or the other is attained by reducing the pressure on one face of the piston and at the same time increasing the pressure on the opposite face. This provides for attaining the required differential on the piston in substantially one half the time attained in structures where the differential is provided by a variation in pressure on one face of the piston only, and as a result the power piston 16 is more quickly responsive to operation of the pilot piston 87. In order that the power piston 16 may be thus controlled, it is necessary that the pressure chambers 17 and 19 both be charged with fluid at some chosen degree of pressure above that of the atmosphere, such as fifty pounds, as above described, when the parts of the apparatus are in their neutral position, as well as when the power piston 16 occupies any position out of neutral as will be apparent.

It will be noted that the pressure of fluid in pressure chambers 17 and 19 constantly acts on the skirt portions 29 and 29a of packing cups 28 and 28a urging same into contact with the wall of the power cylinder and this is desirable in that it provides a substantially fixed degree of

resistance to movement of the piston 16 in the cylinder, so as to thereby hold the rod 25 and the parts connecting said rod with the clutch 3 against creepage from a selected position due for instance to vibration of the installation.

If desired, the annular stop 37 on the piston follower 22 may engage the pressure head 30 of the power cylinder at the time the clutch lever 6 attains "Forward" position and just prior to the control valve lever 50 attaining its neutral position. As a result of the lever 50 being thus held slightly to the left of its neutral position a slight differential of pressures will be maintained on the piston 16 urging same into contact with the pressure head 30 to thereby further secure the piston and connected parts against movement out of the forward position due for instance to vibration of the apparatus. Likewise if the follower 23 is provided with stop 38 it may engage the opposite end of the power cylinder just prior to the control lever 50 being returned completely to its neutral position to thereby maintain a differential of fluid pressures on the piston 16 for holding same against the right-hand end of the power cylinder to avoid creepage of the piston out of this position due to vibration. In case however no stop 38 is provided on follower 23, the differential of pressures just described on piston 16 will act to hold the clutch 3 in its reverse position. Further, the friction of the packing cups 28 and 28a with the cylinder wall and the slight biasing pressures provided on piston 16 in its two extreme positions tends to hold not only the piston but also the piston rod 25 and connected parts against vibration so as to minimize the effect of vibration to create wear.

In the pilot cylinder 43 the piston 87 is of substantially the same construction as power piston 16 in that it is provided with two oppositely arranged packing cups but it should be noted that only one of these packing cups is subject to pressure of fluid at one time and as a result the resistance to movement of the piston is relatively low. Also, vibration will tend to keep the piston 87 in such a state of unrest as to nullify static friction between the piston and cylinder and this is desirable in that it provides for precision adjustment of the piston in its cylinder in accordance with the pressure of fluid supplied to act on either one side or the other of the piston.

The screw threaded connections between the connecting rod 112 and the two links 111 and 113 secured to the opposite ends of said rod provide for adjustment of the distance between the upper end of the lever 105 and the lever 50 of the control valve device 45, as may at times be necessary for adjusting the neutral position or the extreme forward and reverse positions of the piston 16 with respect to the device connected for operation by said piston.

In case the rod is screwed into the links 111 and 113 thereby shortening the distance between the upper end of lever 105 and lever 50 of the control valve device 45, it will be seen that with the lever 50 and the pilot cylinder piston 87 in their neutral positions shown, the lower end of lever 105 will occupy a position slightly to the left of that shown, depending upon the degree of shortening of rod 112, and as a result the neutral position of piston 16 will also be somewhat to the left of that shown. A screwing of the connecting rod 112 out of the links

111 and 113 will move the neutral position of piston 16 to the right of that shown.

The stroke of the piston 16 may also be varied with respect to the predetermined stroke of pilot piston 87 by connecting the link 111 to the lever 105 at a different point than shown in the drawing. For instance the pin 110 may be applied to a bore 116 provided through the lever 105 at a greater distance from the crosshead 107. This increases the distance between the crosshead and the connection with rod 112 which will result in a reduction of stroke of piston 16 for a certain movement of pilot piston 87. In case the connection between rod 112 and lever 105 is changed as just described, the control valve 45 may be also moved upwardly relative to the power cylinder 15 as viewed in Fig. 2 to a position in which the cap screws 47 will be applied to the bores 48 to thereby maintain the connecting rod 112 in substantial parallel relation to the piston rod 25. Any desired number of such adjustments may be provided in the device for adapting same to different uses or the like although only one adjustment is shown for the purpose of illustration.

When the Diesel engine 1, clutch 3, transmission 4, and power shaft 5 constitute parts of a marine craft, these parts as well as the clutch control cylinder 15 and above described associated parts shown in Figs. 1A and 2 will be disposed in the engine room below the deck or bridge floor which for the purpose of illustration is indicated in Fig. 1 by the dash line 120.

According to the invention means are provided for selectively controlling from any one of a plurality of remote stations, such as on the bridge or in the engine room of the craft, the operation of the pilot cylinder device 43 and thereby the control cylinder 15 for positioning the clutch 3. This means comprises a clutch control valve 121 located on the bridge for operation by the pilot of the craft, a like clutch control valve 122 located in the engine room for operation by the engineer and a selector valve 123 also located in the engine room for adjustment by the engineer to render either the control valve 121 or the control valve 122 effective and the other ineffective.

The selector valve 123 comprises a casing having a chamber 127 which is constantly supplied with fluid under pressure from reservoir 63 through pipe 64 and which contains a rotary valve 124 connected by a shaft 125 to an operating handle 126. The rotary valve is movable to either one of two positions, one position, shown in Fig. 1, to provide for control of the clutch 3 from the pilot's control valve 121 and another position shown in Fig. 3 which provides for control of the clutch from the engineer's control valve 122.

In the position of rotary valve 124 shown in Fig. 1 a port 128 therein connects the rotary valve chamber 124 to a pipe 129 for supplying fluid under pressure from the reservoir 63 to the control valve 121, while a cavity 130 in the valve connects a corresponding pipe 131 leading to the control valve 122 to an atmospheric port 132.

In the engine room control position of the selector valve shown in Fig. 3 the supply of fluid under pressure to the pipe 129 is cut off and said pipe is connected through cavity 130 to the atmospheric port 132, while the pipe 131 leading to the engineer's control valve 122 is supplied with fluid under pressure from the rotary valve chamber 127 through a port 134 in the rotary valve.

The pilot's control valve 121 is provided for supplying fluid under pressure from the pipe 129

to either one of two pipes 135 or 136 and for at the same time venting the other pipe and to this end may comprise two self-lapping valve mechanisms of the same structure as the valve mechanisms 58 and 59 contained in the clutch control valve 45 shown in Fig. 2. The valve device 121 may further comprise a handle 137 for operation by the pilot to selectively control the operation of the two valve mechanisms therein.

The handle 137 may have a neutral position in which it is shown for opening both of the pipes 135 and 136 to the atmosphere. Movement of the handle 137 in the direction of a line 138 through a zone of travel indicated by the legend "Forward" is adapted to operate one of the valve mechanisms in the device to provide fluid in the pipe 135 at a pressure dependent upon the position of the handle in said zone, the maximum degree of pressure being attained with the handle in the position indicated by line 138. Movement of the handle 137 in the opposite direction through a zone indicated by the legend "Reverse" is adapted to operate the other valve mechanism in the device to provide fluid at a pressure in the pipe 136 dependent upon the position of the handle in the zone, the maximum degree of pressure being attained in said pipe when the handle is in a position indicated by the line 138. If desired, suitable means (not shown) may be associated with the control valve device 121 for holding the handle 137 in any selected position out of neutral without manual effort.

The engineer's control valve device 122 may be identical to the pilot's control valve device 121 but arranged to selectively control the pressure of fluid in two pipes 140 and 141.

In view of the fact that both of the control valve devices 121 and 122 may be generally similar to the power cylinder control valve device 45, or to a manually operative device of this type which is fully disclosed and claimed in a copending application of Rankin, J. Bush and William H. Glass, Serial No. 400,266, filed June 28, 1941, which has eventuated in Patent No. 2,329,742, dated September 21, 1943, and also for the purpose of simplicity in the present application, a further description thereof will not be provided herein.

The pipes 135 and 140 connected to the two control valves 121 and 122 lead to the opposite ends of a double check valve 145 the side outlet of which is connected to the pilot cylinder control pipe 89. The pipes 136 and 141 connected to the two control valve devices 121 and 122 lead to the opposite ends of a double check valve 146 the side outlet of which is connected to the pilot control cylinder pipe 91. The double check valves 145 and 146 may be of usual structure containing a double ended valve operative upon supply of fluid under pressure through the pipe connected to one end to open communication between said pipe and the side outlet and to close communication between the side outlet and the other end pipe, while upon the supply of fluid under pressure to the other end pipe the double check valve will open communication therebetween and the side outlet and close the other communication.

With the selector valve 123 in the bridge control position shown in Fig. 1, the fluid pressure supply pipe 131 leading to the engineer's control valve 122 is open to the atmosphere as above mentioned so as to render said control valve ineffective to vary the pressure of fluid in either of pipes 140 and 141 and thereby ineffective to

control operation of the power cylinder 15 and clutch 3, as will be apparent from the description to follow. In this position of the selector valve 123 fluid under pressure is supplied through pipe 129 to the pilot's control valve 121 which provides for control of the clutch 3 by the pilot.

If now the pilot desires to cause the craft to move in a forward direction, he rocks the lever 137 in a counterclockwise direction from the neutral position shown to thereby supply fluid under pressure from the pipe 129 to the pipe 135 through which it flows to one end of the double check valve 145 for operating same to open communication between the pipe 135 and 89 leading to the pilot cylinder 43. The pilot piston 87 is thereby subjected to the pressure of fluid supplied by the pilot's control valve 121 which moves same to a position dependent upon the degree of such pressure and causes a corresponding positioning of the clutch control piston 16 and of the clutch 3 controlled by said piston. Movement of the lever 137 to the position indicated by line 138 will provide a pressure through the pipes 135 and 89 on pilot piston 87 to effect full stroke thereof in the direction of the left-hand and thereby movement of the piston 16 to the position for causing full engagement of the clutch. Any lesser degree of movement of the handle 137 from neutral position will cause a correspondingly less degree of engagement of the clutch 3 as will be seen.

If the pilot desires to move the craft backwards, he moves the lever 137 in the direction of the line 139 and in so doing causes fluid under pressure to be supplied from pipe 129 to pipe 136 and thence through the double check valve 146 and pipe 91 to the left-hand face of the pilot piston 87 which responds to such pressure to cause operation of the piston 16 to move the clutch 3 in the direction of the reverse position to either the full reverse position or an intermediate position providing for slipping of the clutch, as determined by the extent of movement of the control valve handle 137 out of the neutral position.

When the pilot desires to neutralize the clutch 3 for disconnecting the engine 1 from the drive shaft 5, he moves the handle 137 to the neutral position shown for thereby venting both of the pipes 135 and 136 to the atmosphere. As a result the opposite sides of the pilot piston 87 will be both opened to the atmosphere and said piston and consequently the clutch control piston 16 will be returned to their neutral positions shown in Fig. 2 for neutralizing the clutch 3.

If for any reason the engineer desires to control the operation of the clutch 3 from the engine room, he operates the handle 126 of the selector valve 123 to turn the rotary valve 124 therein to the engine room control position shown in Fig. 3 to thereby supply fluid under pressure through the pipe 131 to the control valve 122 and to cut off the supply of fluid under pressure to pipe 129 leading to the pilot's control valve device 121. With the pipe 129 thus void of fluid pressure it will be apparent that no fluid pressure can be supplied to either of the pipes 135 or 136 by operation of the pilot's control valve device 121 so that said device is rendered ineffective. However, the supply of fluid under pressure through pipe 131 to the engineer's control valve device 122 provides for selective control of the clutch 3 through the pipes 141 and 140, double check valves 145 and 146 and pipes 89 and 91, respectively, in the same manner as described

15

above in connection with the control by the pilot's control valve device 121.

Since the supply of fluid under pressure to pipe 131 is cut off by the selector valve 123 in the bridge control position shown in Fig. 1, the engineer's control valve device 122 is rendered ineffective when the pilot's control valve device 121 is rendered effective for controlling the clutch 3. It will thus be seen that only one of the control valve devices 121 or 122 may be effective 15 at one time for controlling the clutch 3 and which one is effective is determined by the position of the selector valve device 123 in the engine room. Thus in case of failure of either one of the control valves the other may take over the control of the clutch. The system thus provides for normal control of the clutch by the pilot when he so desires or is in a position or condition to properly execute such control, otherwise this control may be taken on by the engineer below deck.

It will be seen that regardless of the location of the engine 1, the clutch 3, and the clutch cylinder 16 and associated parts of the apparatus on the craft, the control valves 121 and 122 may be located wherever necessary or desired to provide a selective, pneumatic remote control of the clutch.

If for any reason some part of the clutch control apparatus should fail which would prevent control of the clutch from the bridge and engineroom, such for example as breakage of pipe 88 or pipe 81, it is of course desirable for the engineer to be able to position the clutch 3 by hand by manual operation of the clutch control lever 6. This lever may be provided with an extension 200 for this purpose if desired. To facilitate such manual operation it is also desirable that the control chambers 17 and 19 at opposite sides of the piston 16 be substantially at atmosphere pressure. However, if under this condition the reservoir 63 and pipe 64 are intact, the chambers 17 and 19 will be charged with fluid under pressure and it is therefore desirable to release such pressure for unloading the piston 16.

To release the fluid pressure from chambers 17 and 19 under a condition such as just described a cock 201 is provided in pipe 64 between the reservoir 63 and the control valve 45. This cock comprises a casing containing a rotary plug valve 202 having a normal position in which it is shown and a cut off position substantially ninety degrees from the normal position. A handle 203 is provided for turning the plug valve to its different positions, the handle being shown in the normal position of the plug valve while a line 204 indicates the position which the handle will assume in cut off position of the valve.

The plug valve 202 has a waterway 205 for opening communication through the pipe 64 to the clutch control valve 45. In cut off position of the plug valve this communication is closed and the portion of pipe 64 connected with the control valve 45 is vented to the atmosphere through a port 206 in said valve, waterway 205 and a vent port 207 in the cock casing. When this occurs the pressure of fluid in chamber 68 of the valve devices 58 and 59 may unseat the supply valve 61 against their seating springs 73 since the supply valve chambers 73 are vented through the cock 201, or if this does not automatically occur when the cock is turned to cut off position, a slight manual movement of lever 50 first in one direction and then the opposite direction will cause a sufficient increase in pres-

sure of the springs 77 to cause such unseating. Once the valves 61 are unseated, however, fluid under pressure will start to be released from the clutch piston chamber 17 and 19 past said valves to pipe 64 and thence through the cock 201 and such reduction in pressure on the pistons 74 in the devices 58 and 59 will permit springs 77 to maintain the valves 61 open and thus ensure a complete release of fluid under pressure from the chambers 17 and 19. With these chambers vented the clutch 3 may then be operated manually by lever 6.

Control of starting of engine 1

On marine craft it is desirable that the operator at the selected control station, be it the pilot's station or that of the engineer, be capable of starting the engine 1 and also controlling the fuel supply device 10 for determining the speed or power of said engine.

To thus control the starting of engine 1 there is provided a starter control valve device 150 above deck for operation by the pilot and another similar device 151 in the engineer room for operation by the engineer.

The starter control valves 150 and 151 may be similar to the clutch control valves 121 and 122 except including only one valve mechanism arranged to supply fluid under pressure from pipes 129 and 131 to pipes 153 and 154, respectively, upon movement of a control lever 152 in the direction of the right-hand from a normal position. With the lever 152 of the devices 150 and 151 in the normal positions shown, said devices are adapted to vent pipes 153 and 154, respectively.

Since the pipe 129 is supplied with fluid under pressure by the selector valve device 123 only in the position shown in Fig. 1 and is vented in the other position of the selector valve, it will be seen that the starter control valve 150 on the bridge will be effective to supply fluid to the pipe 153 for starting engine 1 only when the selector valve 123 is in the position providing for control of the clutch 3 by operation of the pilot's control valve device 121. Likewise the starter control valve 151 in the engine room will be effective to supply fluid under pressure to pipe 154 for starting the engine 1 only when the selector valve device 123 is in the position providing for control of the clutch 3 by the engineer's control valve device 122.

Fluid under pressure supplied to either of the pipes 153 or 154 by either of the starter control valves 150 or 151 is adapted to flow through a double check valve device 155 to a pipe 156 which leads to a pressure relay valve device 157. This relay valve device may be of any suitable well known structure adapted to be operated by the pressure of fluid supplied through the double check valve device 155 to open communication between a reservoir 158 containing starting fluid at a desired high pressure, and the starter pipe 2 so that fluid from said reservoir 158 may flow to the starter pipe 2 for starting the engine 1. After the engine 1 is started, the starter control valve 150 or 151 may be returned to its normal position shown for thereby releasing fluid under pressure from the relay valve device 157 to effect operation thereof for closing communication between the starter reservoir 158 and the starter pipe 2.

From the above description it will be apparent that only one of the starter valves 150 or 151 will

be effective at one time as determined by the position of the selector valve device 123 which also controls the clutch control valves 121 and 122. Thus when the selector valve device is in the position providing for control of the clutch 3 from the bridge by operation of the pilot's control valve device 121, the starter valve device 150 on the bridge will be rendered effective to control the starting of engine 1, while with the selector valve device in the other position providing for control of the clutch 3 by the engineer's control valve device 122 the starter valve 151 will be effective.

Control of fuel supply to engine 1

The arm 11 of the fuel supply device 10 of the engine 1 is connected by a link 160 to one end of a lever 161 the other end of which is connected by a link 162 to a manually operative control lever 163. The lever 163 is pivotally mounted on a pin 164 and is adapted to move relative to a quadrant rack 165. A spring pressure detent or latch 166 associated with the lever 163 is provided to cooperate with the rack 165 for holding the lever 163 in a selected position and to oppose movement from one position to another.

The lever 161 is connected intermediate its ends to one end of a rod 167 which extends into a cylinder 168 wherein the other end of the rod is connected to a piston 169. At the rod side of the piston 169 is a chamber 170 containing a coil spring 171 which encircles the rod and bears against the piston. At the opposite side of the piston is a pressure chamber 172.

When the chamber 172 is at substantially atmospheric pressure, the pressure of spring 171 is adapted to hold the piston 169 in engagement with one or more stops 173 to provide a fixed fulcrum for lever 161 at its connection with the end of the piston rod 167. Under this condition, the lever 161 may therefore be rocked by the hand lever 163 upon movement thereof relative to the rack 165 by the engineer. Thus if the engineer moves the lever 163 in an upwardly direction from the idling position shown, the rocking of lever 161 in a clockwise direction will move the arm 11 in a counterclockwise direction from the idling position in which it is shown in the direction of the full speed position indicated, to provide any desired selected speed or power of engine 1. Movement of lever 163 in the reverse direction by the engineer will actuate lever 161 to lift the arm 11 for reducing the speed or power of the engine 1.

The pressure chamber 172 in the cylinder 168 is connected by a pipe 174 to a manually operative control valve 175 provided above deck on the bridge for operation by the pilot. The device 175 may be generally like that disclosed in Patent No. 1,939,907, issued to E. K. Lynn on December 19, 1933, and therefore operative to either open the pipe 174 and connect piston chamber 172 to the atmosphere or to supply fluid to said pipe at a pressure depending upon the extent of movement of an operating handle 176 from a position in which the pipe 174 is vented.

The control valve 175 is connected to the pipe 129 which constitutes the source from which fluid pressure may be attained for supply to the pipe 174. Thus the valve device 175 will be effective to vary the pressure of fluid in pipe 174 only when the selector valve device 123 is in the position providing for control of the clutch 3 and starting of the engine from the bridge.

Associated with the lever 163 for controlling the fuel supply device 10 is a cylinder 176a contain-

ing a piston 177 having at one side a pressure chamber 178 connected to the pipe 129 and having at the opposite side a chamber 179 containing a spring 180 acting on the piston 177 for urging same in the direction of the left-hand. The piston is connected to a rod 181 which extends through the spring 180 and chamber 179 to the exterior of the cylinder where it is aligned with an arm 182 projecting from the manually operative lever 163.

When the selector valve device 123 is in the position providing for control of the engine 1 from the engine room and the pipe 129 is as a consequence vented the piston chamber 178 in the cylinder 176a is likewise vented due to being open to the pipe 129 through a pipe 183. Under this condition spring 180 will therefore move the piston 177 into engagement with stops 185 provided at the lefthand end of the cylinder 176 and this movement is adapted to pull the piston rod 181 into the cylinder and sufficiently away from the arm 182 projecting from the lever 163 to permit the engineer to move the lever 163 relative to the rack 165 for controlling the engine speed or power as above described.

However, when the selector valve device 123 is moved to the position shown in Fig. 1 to provide for control of the engine from the bridge, fluid at the pressure supplied to pipe 129 flows through the pipe 183 to chamber 178 in the cylinder 176a and therein acts on the piston 177 to urge same to the position shown. In this position the end of the piston rod 181 engages the arm 182 projecting from the lever 163 for thereby holding said lever in the engine idling position shown and to prevent operation of said lever by the engineer in the engine room. In case the lever 163 should be in a position out of idling at the time the selector valve device is moved to the position shown in Fig. 1, the piston 177 in the cylinder 176a is adapted to move the lever 163 relative to the rack to the idling position and then hold same in said position, as above mentioned.

With pipe 129 supplied with fluid under pressure to provide for control of the engine and clutch from the bridge the pilot may operate the control valve device 175 to supply fluid at any desired pressure from pipe 129 to the pipe 174 and thence to piston chamber 172 in the cylinder 168. This pressure acting on piston 169 is adapted to move same against spring 171 to thereby rock the lever 161 in a clockwise direction about its pivotal connection with link 162, and thus rock the arm 11 out of the idling position shown in the direction of the full speed position to thereby accelerate or increase the speed or power of the engine 1. The piston 169 will be moved to a position in cylinder 168 dependent upon the pressure of fluid supplied to chamber 172 by operation of the control valve 175 and the opposing pressure of the spring 171, and the arm 11 of the fuel supply device will therefore be moved to a corresponding position. Thus by properly adjusting the control valve device 175 and thereby the pressure of fluid supplied to pipe 174 the arm 11 of the fuel supply device may be moved to any chosen position from idling to full speed to provide any chosen degree of speed or power of the engine.

From the above description it will now be seen that the starting of the engine 1, the control of the engine clutch 3, and the control of the speed or power of the engine is arranged for control remotely either from the bridge of the craft by operation of the manually operative devices 150,

(21, and 175 respectively, or from the engine room by manual operation of the devices 151 and 122 and of the manually operative lever 163, dependent upon the position of the selector valve device 123 which is located in the engine room for adjustment by the engineer. When the selector valve device 123 is in the position providing for control of these parts from the bridge, all control from the engine room is prevented. Likewise when the selector valve device is in the position providing for control from the engine room the control devices on the bridge are rendered ineffective. It will also be seen that failure of the manual control devices on the bridge will not result in loss of control of the craft since such control may completely be taken over by the engineer in the engine room.

In order to insure control of the craft from the engine room in case for instance of destruction of the pilot's control station, the double check valves 145 and 146 and the pipes 89 and 91 connected to the side outlets thereof would of course be located below the deck floor 120, although for the purpose of simplicity they are shown in the illustration at a level above said floor.

Description—Figure 4

It is desirable that the speed of engine 1 be substantially at idling when the clutch is in neutral position or at the time the clutch is moved from neutral position to either of its drive positions. This may of course be insured by the pilot returning handle 176 of the valve device 175 to the position providing for idling of the engine or by the engineer moving the lever 163 to the idling position shown, dependent upon the control station. Such manual adjustment on the part of the operator from the control station is usually adequate, but if desired the apparatus shown in Figs. 1—1A may be modified as shown in Fig. 4 to accomplish this end automatically from the bridge.

According to this modification I provide a valve device 210 for controlling communication between the pipe 174 from the valve device 175 located in the pilot house and a pipe 211 which is connected to the fuel control cylinder 168.

The valve device 210 has a chamber 212 to which the pipe 174 is connected and which contains a poppet valve 213 controlling communication between the chamber 212 and a chamber 214 which is connected to the pipe 211. A spring 215 in chamber 212 acts on the valve 213 for urging same to its closed position in which it is shown.

The poppet valve 213 has a fluted stem extending through a suitable bore into the chamber 214 wherein it engages the fluted stem of an oppositely arranged poppet valve 216 which is contained in a chamber 217 open to the atmosphere through a vent port 218. The chamber 217 is formed at one side of a piston 219 which is connected to the valve 216 and which has at the opposite side a chamber 220 connected by a pipe 221 to the side outlet of a double check valve device 222. One end outlet of the double check valve device 222 is connected to the pilot cylinder control pipe 91 while the other end outlet is connected to the pilot control cylinder pipe 89.

When the pipes 89 and 91 are both vented for neutralizing the clutch control power piston 16, the piston chamber 220 in the device 210 will likewise be vented through either one or the other of said pipes to thereby provide for seating of the valve 213 by the spring 215. Under this condition the pressure chamber 172 in the cylinder

168 will be open to the atmosphere past the valve 216 to thereby permit spring 171 in said cylinder to move the piston 169 to its uppermost position for thereby causing movement of the fuel supply valve device operating arm 11 to its idling position, with the engineer's control lever 163 in its idling position. Thus with the clutch neutralized the speed of the engine 1 will be reduced to idling.

When fluid under pressure is supplied to either one of the pilot cylinder control pipes 89 or 91 for causing movement of the clutch out of neutral position, as herein before described, such pressure is adapted to be transmitted through the double check valve device 222 and pipe 221 to piston chamber 220 in the device 210 for acting on the piston 219 to cause movement thereof in the direction of the left-hand to seat the valve 216 and unseat the valve 213. With the valve 213 thus open the fuel supply control cylinder 168 is connected to the pilot's valve 175 on the bridge whereby the speed and power of the engine may be controlled by the pilot as previously described. Upon subsequent venting of the pilot cylinder control pipe 89 or 91 for neutralizing the clutch

25 3 a corresponding venting of fluid from piston chamber 220 in the device 210 will occur through the double check valve 222 and the respective pilot cylinder control pipe which will permit spring 215 to close the valve 213 and open the valve 216 to thereby release fluid under pressure from the fuel supply control cylinder 168. As a result, spring 171 acting on the piston 169 will operate the lever 161 to return the fuel supply

30 40 device control arm 11 to its idling position to thereby cause idling of the engine. It will thus be seen that in controlling the engine from the pilot house the structure shown in Fig. 4 will insure that the throttle control cylinder will be adjusted to provide for operation of the engine at idling speed whenever the clutch is in neutral position, but upon movement of the clutch out of neutral position toward either its forward or reverse positions, the fluid pressure supplied to either pipe 91 or 89 to cause such movement will operate the device 210 to connect the fuel supply device 10 to the manually operative control device 175 on the bridge so that the pilot may then take over the control of the speed and power

45 50 of the engine.

When the engine is being controlled from the engine room as will be rare when the pilot's control devices on the bridge are capable of control, it is of course essential for the engineer to move the lever 163 to idling position when the clutch is neutralized. The possibility of failure to do this on the part of the engineer is however very remote on account of his proximity to the engine 1 and therefore his constant awareness of the speed condition of the engine.

Description—Figure 5

Neutralizing of the piston 16 in the power cylinder 15 of the structure shown in Fig. 2 is attained by destruction of the moving force or pressure differential on said piston, and this is obtained by equalization of the pressures on opposite sides of the piston at the time the neutral position of the piston is reached, so that movement of the piston will cease in such position. If desired, however, a power structure such as shown diagrammatically in Fig. 5 may be employed in place of the power cylinder 15, this structure having positive stops for defining the

neutral position of the clutch or other member being controlled.

In the structure shown in Fig. 5 the lever 6 of the clutch 3 or other member to be controlled is connected by the eye bolt 35 and link 34 to a lever 225 intermediate the ends thereof. One end of this lever is connected to one end of a rod 226 projecting from a cylinder 227 while the other end of the lever is connected to a rod 228 projecting from a cylinder 229, the cylinders 227 and 229 being arranged to operate oppositely.

In the cylinder 227 the other end of the rod 226 is connected to a piston 230 which has at one side a chamber 231 open to a pipe 232. At the opposite side of piston 230 is a coil spring 233 acting on the piston for urging same in the direction of pipe 232 and into contact with stops 234. The cylinder 229 has a corresponding piston 235, spring 236 acting on the piston, stops 237 for engagement by the piston under the action of said spring, and a pressure chamber 238 which is open to a pipe 239.

With both pipes 232 and 239, and thereby pressure chambers 231 and 238 void of fluid pressure, the springs 233 and 236 will maintain the pistons 230 and 235 in contact with the respective stops 234 and 237 to thereby define the neutral position of the clutch operating lever 6.

In order to move the clutch to its forward position or any intermediate position, the pipe 239 and pressure chamber 238 are maintained open to the atmosphere through any suitable valve and at the same time fluid under pressure is supplied to the pipe 232 and thereby pressure chamber 231 for moving the piston 230 against the spring 233. At this time the connection between the upper end of lever 225 and the piston rod 226 constitutes a fixed fulcrum for said lever so that as the piston 230 in the cylinder 227 is moved against the spring 233 the lever 225 will be rocked in a clockwise direction to thereby effect movement of the clutch operating lever 6 from the neutral position shown in the direction of the forward position. The degree of this movement will be determined by the pressure of fluid supplied to act on the piston 230 and the opposing force of control spring 233, and by varying this pressure the clutch operating arm 6 can be moved to either full forward position or to any intermediate position to attain a desired degree of engagement.

Now in order to move the clutch to reverse position the pipe 232 and pressure chamber 231 in the cylinder 227 will be maintained at atmospheric pressure and fluid under pressure will be supplied through pipe 239 to pressure chamber 238 in the cylinder 229 and therein act to move the piston 235 in the direction of the right-hand. Under this condition the connection between the lever 225 and piston rod 226 constitutes a fixed fulcrum for said lever so that the lever will be rocked in a clockwise direction to thereby pull the clutch operating lever 6 out of neutral position and in the direction of reverse position. The degree of this movement of lever 6 and thereby the degree of engagement of the clutch may be adjusted in accordance with the pressure of fluid supplied to act on the piston 235 as will be apparent.

In order to neutralize the clutch from either the forward or reverse position the pressure chambers 231 and 238 in both of the cylinders 227 and 229 will be opened to the atmosphere to thereby permit the springs 233 and 236 to urge the pistons 230 and 235 into engagement with the re-

spective stops 234 and 237, and in so doing return the lever 225 and clutch operating arm 6 to their neutral positions shown and as accurately defined by engagement between said pistons and their respective stops.

In this modification it will be noted that one of the pipes 232 and 239 is vented when the other is supplied with fluid under pressure. For controlling the pressure in these pipes they may therefore be connected for direct-control to a control valve like the pilot's control valve 121 shown in Fig. 1, or they may be connected up to the clutch control valve 45 shown in Fig. 2 in which case however it will be necessary to adjust the screws 79 controlling the self-lapping valve devices 58 and 59 to provide for complete release of fluid under pressure from both of the pipes when the operating lever 50 occupies its neutral position.

Summary

From the above description it will now be seen that a relative simple and effective control system has been provided for selectively controlling the starting of an engine, such as a Diesel engine, the fuel supply to said engine, and the selective operation of a power mechanism to operate a device such as an engine clutch. The system embodies manually operative means for selectively controlling pneumatically the operations just mentioned from any chosen one of a number of remote control stations, and other means are provided for selectively determining the control station which is to be effective and for rendering the other station ineffective.

The power mechanism for operating the device, such as a clutch, is capable of immediate response to operation of a manual control device to promptly and accurately effect a selected operation determined by the operation of the manual control device. It will be noted that the power cylinder control valve 45 is mounted directly on the power cylinder so as to provide for the shortest possible pipe connection between said device and cylinder in order that said device may cause relatively rapid changes in pressure on the opposite sides of the power piston 16 as required for prompt response thereof to operation of the control valve 45. The relatively small pilot cylinder 43 associated with the cylinder 16 is remotely controlled from the controllers 121 or 122, but the amount of air required for controlling this device 3 is relatively small as compared to that required for operating the power piston 16 and this provides for prompt response of the pilot piston 87 to any selected operation of the remotely located control valves 121 or 122.

Having now described my invention, what I claim as new and desire to secure by Letters Patent, is:

1. In combination, a device to be operated, a motor controlled by fluid under pressure for controlling operation of said device, a source of fluid under pressure, a manual control device operative when connected with said source of fluid under pressure to control operation of said motor, another manual control device operative when connected with said source of fluid under pressure to control operation of said motor, and a selector valve device having one position for connecting one of said manual control devices to said source of fluid under pressure and for disconnecting the other manual control device from said source of fluid under pressure and having another position for connecting said other man-

ual control device with said source of fluid under pressure and disconnecting said one manual control device from said source of fluid under pressure.

2. In combination, a device to be operated, a motor operative in accordance with the supply and release of fluid under pressure to and from a pipe to control operation of said device, a source of fluid under pressure, two separate manual control devices each having a normal position for venting fluid under pressure from said pipe and being operative upon movement out of normal position to supply fluid under pressure from said source to said pipe, a selector valve device controlling communication between said source and said manual control devices and having one position for opening communication between said source and one of said manual control devices and for closing communication between said source and the other manual control device and having another position for opening communication between said other manual control device and said source and for closing communication between said source and said one manual control device, and a double check valve device controlling communication between said manual control devices and pipe and operative by fluid under pressure supplied by one of said manual control devices to open communication therebetween and said pipe and to close communication between said pipe and the other manual control device.

3. In combination, a device to be operated, a double acting fluid motor operative in accordance with the supply and release of fluid under pressure to either one or another of two pipes to control operation of said device, a source of fluid under pressure, a manual control device having a normal position for venting both of said pipes and operative upon a certain movement from normal position to supply fluid under pressure from said source to one of said pipes and upon a certain different movement from normal position to supply fluid under pressure from said source to the other of said pipes and operative when supplying fluid under pressure to either one of said pipes to open the other pipe to the atmosphere, another manual control device having a normal position for venting both of said pipes and operative upon a certain movement from normal position to supply fluid under pressure to one of said pipes and upon a certain different movement from normal position to supply fluid under pressure to the other of said pipes and operative when supplying fluid under pressure to either one of said pipes to open the other pipe to atmosphere, a selector valve device for connecting said manual control devices with said source of fluid pressure to provide fluid under pressure to said devices for supply to said pipes, said selector valve device having one position for closing communication between said source and one of said manual control devices and for opening communication between said source and the other manual control device, and another position for opening communication between said source and the said other manual control device and for closing communication between said source and the said one manual control device, and a double check valve device controlling communication between each of said pipes and the two manual control devices, each of said double check valve devices being operative by fluid under pressure supplied by one of said manual control devices to open communica-

tion therebetween and the connected pipe and to close communication between such pipe and the other manual control device.

4. In combination, a device having a plurality of different operating positions, a motor operative upon supply of fluid under pressure to a pipe to move said device to a position depending upon the pressure of fluid supplied to said pipe, a source of fluid pressure, a manual control device comprising an operating member having a normal position providing for the release of fluid under pressure from said pipe and being operative upon movement out of said normal position to supply fluid from said source to said pipe at a pressure which varies in accordance with the extent of movement of said member from normal position, another manual control device comprising an operating member having a normal position providing for release of fluid under pressure from said pipe and being operative upon movement out of normal position to supply fluid under pressure from said source to said pipe at a pressure which varies in accordance with the extent of movement of the member from normal position, a double check valve controlling communication between said pipe and the two said manual control devices and being operative by fluid under pressure supplied by either of said manual control devices to open communication therebetween and said pipe and to close communication between said pipe and the other manual control device, and a selector valve controlling communication between said source and said manual control devices and having one position for opening communication between said source and one of said manual control devices and for closing communication between said source and the other manual control device, said selector valve being movable from said one position to another position for closing communication between said source of fluid pressure and the said one manual control device and for opening communication between said source and the said other manual control device.

5. In combination, a propulsion engine, a device for controlling the power output of said engine, said device having an idling position to provide for idling of said engine and a position to provide for maximum engine output and being adjustable to any selected intermediate position to provide different degrees of engine output, a spring, a movable abutment having a connection with said device controlled by the opposing pressures of said spring and of fluid in a chamber and being operative to move said device to a position dependent upon the pressure of fluid in said chamber, a source of fluid under pressure, a manually operative valve for supplying various degrees of fluid pressure from said source to said chamber to control the position of said device, and a valve device controlling communication between said source and manually operative valve and having one position for opening said communication to render said device controllable by said manually operative valve and having another position for closing said communication to render said device non-controllable by said manually operative valve.

6. In combination, a propulsion engine, a device for controlling the power output of said engine, said device having an idling position to provide for idling of said engine and a position to provide for maximum engine output and being adjustable to any selected intermediate position to provide various chosen lesser degrees of output,

25

a spring, a movable abutment having a connection with said device and controlled by the opposing pressure of said spring and of fluid in a chamber, said spring being operative when said chamber is void of fluid under pressure to actuate said abutment to move said device to idling position, said abutment being operative upon supply of fluid under pressure to said chamber to move said device out of idling position to an extent dependent upon the pressure of such fluid, a source of fluid pressure, a manually operative valve having a normal position for venting said chamber to the atmosphere and being operative upon movement out of normal position to supply various degrees of fluid pressure from said source to said chamber to control the operation of said abutment to position said device, a lever for manually operating said device, said lever having an idling position and being movable therefrom to any one of a plurality of different positions to actuate said device to provide various degrees of engine output, and means connecting said lever and abutment to said device and conditionable by said lever in its idling position to render said device adjustable in accordance with the position of said abutment, said means being conditionable by said abutment when said chamber is void of fluid under pressure to render said device adjustable in accordance with movement of said lever.

7. In combination, a propulsion engine, a fuel control device for controlling the power output of said engine, said device having an idling position to provide for idling of said engine, and a position to provide maximum output and being adjustable to any selected intermediate position to provide various different degrees of engine output, a spring, a movable abutment connected to said device and controlled by the opposing pressures of said spring and the pressure of fluid in a chamber, said spring being operative when said chamber is void of fluid pressure to actuate said abutment to move said device to said idling position, said abutment being operative upon supply of fluid under pressure to said chamber to actuate said device to a position out of idling for providing an engine output proportional to the pressure of fluid in said chamber, a source of fluid pressure, a manual control valve having a normal position for venting fluid under pressure from said chamber and being movable out of normal position to supply fluid from said source to said chamber at a pressure required to provide a desired engine output, a selector valve device controlling the supply of fluid under pressure from said source to said control valve and having one position for cutting off such supply to thereby render said control valve ineffective to supply fluid under pressure to said chamber and having another position providing for such supply to render said control valve effective to control said abutment, a lever connected with said fuel control device and operative manually to also adjust same to provide a chosen engine output, said lever having an idling position providing for idling of said engine and being movable therefrom for adjusting said fuel control device to provide a chosen output of said engine, means connecting said abutment and lever with said fuel supply device, said means being conditionable by said abutment when in its idling position to render said lever effective to adjust the position of said fuel supply device and conditionable by said lever in its idling position for rendering said abutment effective to control the position of said fuel supply device, and means operative upon movement

26

of said selector valve device to the position for supplying fluid under pressure to said control valve to move said lever to and hold same in its idling position to provide for control of said device by said abutment.

8. In combination, a propulsion engine, a fuel control device for controlling the power output of said engine, said device having an idling position to provide for idling of said engine, and a position to provide maximum output and being adjustable to any selected intermediate position to provide various different degrees of engine output, a spring, a movable abutment connected to said device and controlled by the opposing pressures of said spring and the pressure of fluid in a chamber, said spring being operative when said chamber is void of fluid pressure to actuate said abutment to move said device to said idling position, said abutment being operative upon supply of fluid under pressure to said chamber to actuate said device to a position out of idling for providing an engine output proportional to the pressure of fluid in said chamber, a source of fluid pressure, a manual control valve having a normal position for venting fluid under pressure from said chamber and being movable out of normal position to supply fluid from said source to said chamber at a pressure required to provide a desired engine output, a selector valve device controlling the supply of fluid under pressure from said source to said control valve and having one position for cutting off such supply to thereby render said control valve ineffective to supply fluid under pressure to said chamber and having another position providing for such supply to render said control valve effective to control said abutment, a lever connected with said fuel control device and operative manually to also adjust same to provide a chosen engine output, said lever having an idling position providing for idling of said engine and being movable therefrom for adjusting said fuel control device to provide a chosen output of said engine, means connecting said abutment and lever with said fuel supply device, said means being conditionable by said abutment when in its idling position to render said lever effective to adjust the position of said fuel supply device and conditionable by said lever in its idling position for rendering said abutment effective to control the position of said fuel supply device, a member subject to pressure of fluid in a control chamber and to an opposing pressure and operative by such fluid pressure to move said lever to and to maintain same in its idling position, and operative by the opposing pressure upon release of fluid pressure from said control chamber to render said lever adjustable manually out of idling position, said control chamber being open to the communication to which fluid under pressure is supplied in the said one position of said selector valve device and vented in the said other position to thereby render said member operable to maintain said lever in its idling position during control of said abutment by said manual control valve and to provide for manual movement of said lever when said valve device is in the position venting said communication.

9. In combination, two devices to be operated, means operable in accordance with variations in fluid pressure for controlling operation of one of said devices, other means operable in accordance with variations in fluid pressure for controlling the operation of the other of the said devices, a pipe, manual control means operable to either

supply fluid under pressure from said pipe to one of said means or to vent fluid under pressure from said one means for effecting variations in pressure thereon to control one of said devices, another manual control means operative to either supply fluid under pressure from said pipe to the said other means or to release fluid under pressure therefrom for effecting variations in pressure thereon for controlling the other of said devices, a selector valve having one position for supplying fluid under pressure to said pipe to render both of said manual control means effective to control the operation of said one and other means and in turn of said devices and having another position for cutting off the supply of fluid under pressure to said pipe for rendering both of said manual control means ineffective to control operation of said means and devices, and means conditionable, upon movement of said selector valve to the position for cutting off the supply of fluid under pressure to said pipe, to control the operation of both of said devices, said selector valve in the position supplying fluid under pressure to said pipe, rendering the last named means ineffective to control the operation of the said devices.

10. In combination two devices to be operated, one means conditionable in accordance with variations in fluid pressure for controlling the operation of one of said devices, another means conditionable in accordance with variations in fluid pressure for controlling the operation of the other of said devices, a pipe, two control valves each adjustable manually to either supply fluid under pressure from said pipe to one of said means or to release fluid under pressure therefrom for controlling the operation thereof and in turn of the respective device, a selector valve having one position for supplying fluid under pressure to said pipe for rendering said control valves effective to control the said respective means and having another position for cutting off the supply of fluid under pressure to said pipe to render said control valves ineffective to control the said respective means, another control valve for controlling said one means and operative to either supply fluid under pressure from a second pipe to said one means or to release fluid under pressure therefrom for effecting said variations in fluid pressure thereon, said selector valve in the position cutting off the supply of fluid under pressure to said one pipe operating to supply fluid under pressure to said second pipe and in the position supplying fluid under pressure to said one pipe cutting off the supply of fluid under pressure to said second pipe, a lever for also controlling the said other device, and means operative upon supply of fluid under pressure to said one pipe to render said lever ineffective and upon release of fluid under pressure from said one pipe effective.

11. In combination, two devices to be operated, one means conditionable in accordance with variations in fluid pressure for controlling the operation of one of said devices, another means conditionable in accordance with variations in fluid pressure for controlling the operation of the other of said devices, a pipe, two control valves each adjustable manually to either supply fluid under pressure from said pipe to one of said means or to release fluid under pressure therefrom for controlling the operation thereof and in turn of the respective device, a selector valve having one position for supplying fluid under pressure to said pipe for rendering said control

valves effective to control the said respective means and having another position for cutting off the supply of fluid under pressure to said pipe to render said control valves ineffective to control the said respective means, another control valve for controlling said one means and operative to either supply fluid under pressure from a second pipe to said one means or to release fluid under pressure therefrom for effecting said variations in fluid pressure thereon, said selector valve in the position cutting off the supply of fluid under pressure to said one pipe operating to supply fluid under pressure to said second pipe and in the position supplying fluid under pressure to said one pipe cutting off the supply of fluid under pressure to said second pipe, a lever for also controlling the operation of the said other device, connector means connecting said lever to said other device and conditionable by said other means upon cutting off the supply of fluid under pressure to said one pipe to render said lever effective to control the operation of said other device, said connector means also controlling the operation of the said other device by the said other means, and means operable upon supply of fluid under pressure to said one pipe to condition said connector means to provide for operation of said other device by said other means.

12. A control system for a clutch for connecting an internal combustion engine to a propeller shaft and having an engaged position and a disengaged position, and for the fuel supply device of said engine, said system comprising in combination a fluid motor operative upon supply of fluid under pressure to a control pipe to effect engagement of said clutch and upon release of fluid pressure from said control pipe disengagement of said clutch, a fluid motor for said fuel supply device operative by fluid under pressure to vary the amount of fuel supplied to said engine in proportion to the pressure of fluid acting thereon, a selector valve manually adjustable to one position for supplying fluid under pressure to a first fluid pressure supply pipe and for cutting off the supply of fluid under pressure to a second fluid pressure supply pipe and to another position for cutting off the supply of fluid under pressure to said first supply pipe and for supplying fluid under pressure to said second supply pipe, two manually operative control valves for said clutch motor each being operative to release fluid under pressure from said control pipe, one of said control valves being operative to supply fluid under pressure from said one supply pipe to said control pipe and the other control valve being operative to supply fluid under pressure from the other supply pipe to said control pipe, means in the connection between said control valves and control pipe operative to close communication between said control pipe and one control valve upon operation of the other control valve to supply fluid under pressure to said control pipe, a third control valve arranged to supply fluid under pressure from said first supply pipe to said fuel supply motor and to release fluid under pressure therefrom for controlling the adjustment of said fuel device, said selector valve in the position venting the said one supply pipe providing for control of said clutch motor by the said control valve connected with said second supply pipe and in the position venting said second supply pipe providing for control of said clutch motor and fuel supply motor by the said control valves connected to said first supply pipe, a lever oper-

ative manually for adjusting said fuel supply device, and means connected to said first supply pipe and operative upon supply of fluid under pressure thereto to hold said lever in a position providing for idling of said engine and operative upon cutting off of the supply of fluid under pressure to said first supply pipe to provide for operation of said lever to control said fuel device.

13. A mechanism for adjusting a fuel supply device of an internal compression engine for controlling the power output of the engine comprising in combination, an adjusting arm for said device, said arm having an idling position for adjusting said device to provide for idling of said engine and being movable from said idling position to effect an increased supply of fuel to said engine dependent upon the extent of such movement, a beam having one connection with said arm, a piston having a pivotal connection with said beam and having at one side a fluid pressure chamber, a spring acting on said piston in opposition to fluid pressure in said chamber, a manually operative lever having a pivotal connection with said beam, said spring being operative when said chamber is void of fluid pressure to position said beam to provide for adjustment of said arm and thereby of said fuel supply device by movement of said lever from an engine idling position, said piston being operative by fluid under pressure supplied to said chamber with said lever in idling position to actuate said beam and thereby operate said arm to adjust said fuel supply device for supplying fuel to said engine in an amount proportional to the pressure of fluid supplied to said chamber and consequent movement of said piston against said spring, and means operative to supply fluid under pressure to and to vent fluid under pressure from said chamber.

14. A mechanism for adjusting a fuel supply device of an internal compression engine for controlling the power output of the engine comprising in combination, an adjusting arm for said device, said arm having an idling position for adjusting said device to provide for idling of said engine and being movable from said idling position to effect an increased supply of fuel to said engine dependent upon the extent of such movement, a beam having one connection with said arm, a piston having a pivotal connection with said beam and having at one side a fluid pressure chamber, a spring acting on said piston in opposition to fluid pressure in said chamber, a manually operative lever having a pivotal connection with said beam, said spring being operative when said chamber is void of fluid pressure to position said beam to provide for adjustment of said arm and thereby of said fuel supply device by movement of said lever from an engine idling position, said piston being operative by fluid under pressure supplied to said chamber with said lever in idling position to actuate said beam and thereby operate said arm to adjust said fuel supply device for supplying fuel to said engine in an amount proportional to the pressure of fluid supplied to said chamber, and consequent movement of said piston against said spring, a second spring, a second piston subject to the opposing pressures of said second spring and of fluid in a control chamber and operative upon supply of fluid under pressure to said control chamber for moving said lever to and for holding same in said idling position to thereby render the first named piston effective to actuate said beam to control the operation of said fuel supply device.

vice and to also prevent operation of said lever out of idling position when said first named piston is effective, the second named spring being operative when said control chamber is void of fluid pressure to actuate said second named piston to a position to provide for operation of said lever to actuate said beam and arm to adjust said fuel supply device, and means operative to selectively supply fluid under pressure to and vent fluid under pressure from both of said chambers.

15. A mechanism for adjusting a fuel supply device of an internal compression engine for controlling the power output of the engine comprising in combination, an adjusting arm for said device, said arm having an idling position for adjusting said device to provide for idling of said engine and being movable from said idling position to effect an increased supply of fuel to said engine dependent upon the extent of such movement, a beam having one connection with said arm, a piston having a pivotal connection with said beam and having at one side a fluid pressure chamber, a spring acting on said piston in opposition to fluid pressure in said chamber, a manually operative lever having a pivotal connection with said beam, said spring being operative when said chamber is void of fluid pressure to position said beam to provide for adjustment of said arm and thereby of said fuel supply device by movement of said lever from an engine idling position, said piston being operative by fluid under pressure supplied to said chamber with said lever in idling position to actuate said beam and thereby operate said arm to adjust said fuel supply device for supplying fuel to said engine in an amount proportional to the pressure of fluid supplied to said chamber, and consequent movement of said piston against said spring, a second spring, a second piston subject to the opposing pressures of said second spring and of fluid in a control chamber and operative upon supply of fluid under pressure to said control chamber for moving said lever to and for holding same in said idling position to thereby render the first named piston effective to actuate said beam to control the operation of said fuel supply device and to also prevent operation of said lever out of idling position when said first named piston is effective, the second named spring being operative when said control chamber is void of fluid pressure to actuate said second named piston to a position to provide for operation of said lever to actuate said beam and arm to adjust said fuel supply device, a manual control valve operative, when fluid under pressure is supplied to a supply pipe, to control the pressure of fluid in said pressure chamber, said control chamber being open to said fluid pressure supply pipe, and a selector valve having one position for supplying fluid under pressure to said supply pipe and another position for cutting off such supply and for venting said pipe, the supply of fluid under pressure to said supply pipe providing for adjustment of said fuel supply device by the first named piston upon operation of said manual control valve and providing for holding of said lever in idling position by said second named piston, and the venting of fluid under pressure from said supply pipe rendering said manual control valve and first named piston ineffective to control the operation of said fuel supply device and rendering the second named piston ineffective to hold said lever in idling position to thereby provide for operation of said fuel supply device by said lever.

16. A system for selectively controlling from

any one of a plurality of control stations, the starting of an internal combustion engine, the adjustment of a fuel supply device for said engine and the engaging and disengaging of a clutch for connecting and disconnecting said engine with and from a propeller shaft, said system comprising in combination a clutch control fluid motor operative upon supply of fluid pressure to a clutch control pipe to effect engagement of said clutch and upon release of fluid under pressure from said pipe to effect disengagement of said clutch, a motor for said fuel device operable by fluid under pressure to adjust said fuel supply device to supply an amount of fuel to said engine proportional to the pressure of the operating fluid, a fluid pressure supply pipe leading to each control station, a manually operative clutch control valve at each control station operable to connect the respective fluid pressure supply pipe to said clutch control pipe for supplying fluid under pressure to actuate said clutch control motor and also operable to release fluid under pressure from said clutch control pipe, a manually operative starter control valve at each of said stations operable to supply fluid under pressure from the respective fluid pressure supply pipe to an engine starting pipe to effect starting of said engine, a fuel control valve at one of said stations operable manually to supply fluid under pressure from the respective fluid pressure supply pipe to said fuel device control motor and to release fluid under pressure therefrom for controlling the operation of such motor, manually operable means at another of said control stations for manually adjusting said fuel supply device and having an idling position for conditioning said fuel supply device to provide for idling operation of said engine, and a selector valve selectively controlling the supply of fluid under pressure to the several fluid pressure supply pipes and adjustable to different positions for in each position supplying fluid under pressure to one of said supply pipes and for cutting off the supply of fluid under pressure to and for venting the other supply pipe.

17. A system for selectively controlling from any one of a plurality of control stations, the starting of an internal combustion engine, the adjustment of fuel supply device for said engine and the engaging and disengaging of a clutch for connecting and disconnecting said engine with and from a propeller shaft, said system comprising in combination a clutch control fluid motor operative upon supply of fluid pressure to a clutch control pipe to effect engagement of said clutch and upon release of fluid under pressure from said pipe to effect disengagement of said clutch, a motor for said fuel device operable by fluid under pressure to adjust said fuel supply device to supply an amount of fuel to said engine proportional to the pressure of the operating fluid, a fluid pressure supply pipe leading to each control station, a manually operative clutch control valve at each control station operable to connect the respective fluid pressure supply pipe to said clutch control pipe for supplying fluid under pressure to actuate said clutch control motor and also operable to release fluid under pressure from said clutch control pipe, a manually operative starter control valve at each of said stations operable to supply fluid under pressure from the respective fluid pressure supply pipe to an engine starting pipe to effect starting of said engine, a fuel control valve at one of said stations operable manually to supply fluid under pressure from the respective fluid pressure supply pipe to said fuel device control motor and to release fluid under pressure therefrom for controlling the operation of such motor, manually operable means at another of said control stations for manually adjusting said fuel supply device and having an idling position for conditioning said fuel supply device to provide for idling operation of said engine, valve means arranged in the communications between said clutch control motor and the manually operative clutch control valves at the plurality of stations and in the communication between said engine starting pipe and the manually operative starter control valves at the plurality of stations operable upon operation of one of the said control valves to supply fluid under pressure to its respective pipe to close communication therebetween and the other control valve connected to such pipe, and a selector valve for selectively controlling the supply of fluid under pressure to the several fluid pressure supply pipes and adjustable to different positions for in each position supplying fluid under pressure to one of said supply pipes and for cutting off the supply of fluid under pressure to and venting the other supply pipe.

device control motor and to release fluid under pressure therefrom for controlling the operation of such motor, manually operable means at another of said control stations for manually adjusting said fuel supply device and having an idling position for conditioning said fuel supply device to provide for idling operation of said engine, a selector valve for selectively controlling the supply of fluid under pressure to the several fluid pressure supply pipes and adjustable to different positions for in each position supplying fluid under pressure to one of said supply pipes and for cutting off the supply of fluid under pressure to and for venting the other supply pipe, and means operable upon supply of fluid under pressure to the supply pipe leading to said one station to hold said manually operable means in said idling position.

18. A system for selectively controlling from any one of a plurality of control stations, the starting of an internal combustion engine, the adjustment of a fuel supply device for said engine and the engaging and disengaging of a clutch for connecting and disconnecting said engine with and from a propeller shaft, said system comprising in combination, a clutch control fluid motor operative upon supply of fluid pressure to a clutch control pipe to effect engagement of said clutch and upon release of fluid under pressure from said pipe to effect disengagement of said clutch, a motor for said fuel device operable by fluid under pressure to adjust said fuel supply device to supply an amount of fuel to said engine proportional to the pressure of the operating fluid, a fluid pressure supply pipe leading to each control station, a manually operative clutch control valve at each control station operable to connect the respective fluid pressure supply pipe to said clutch control pipe for supplying fluid under pressure to actuate said clutch control motor and also operable to release fluid under pressure from said clutch control pipe, a manually operative starter control valve at each of said stations operable to supply fluid under pressure from the respective fluid pressure supply pipe to an engine starting pipe to effect starting of said engine, a fuel control valve at one of said stations operable manually to supply fluid under pressure from the respective fluid pressure supply pipe to said fuel device control motor and to release fluid under pressure therefrom for controlling the operation of such motor, manually operable means at another of said control stations for manually adjusting said fuel supply device and having an idling position for conditioning said fuel supply device to provide for idling operation of said engine, valve means arranged in the communications between said clutch control motor and the manually operative clutch control valves at the plurality of stations and in the communication between said engine starting pipe and the manually operative starter control valves at the plurality of stations operable upon operation of one of the said control valves to supply fluid under pressure to its respective pipe to close communication therebetween and the other control valve connected to such pipe, and a selector valve for selectively controlling the supply of fluid under pressure to the several fluid pressure supply pipes and adjustable to different positions for in each position supplying fluid under pressure to one of said supply pipes and for cutting off the supply of fluid under pressure to and venting the other supply pipe.

19. An arrangement for controlling the operation of a clutch to connect and disconnect an internal combustion engine to and from a propeller shaft and for controlling the adjustment of a fuel supply device for said engine, said arrangement comprising in combination, a clutch control fluid motor operable upon supply of fluid under pressure to a clutch control pipe to effect engagement of said clutch and upon venting of fluid under pressure from said pipe to effect disengagement of said clutch, clutch control means for supplying fluid under pressure to and for venting fluid under pressure from said pipe, a fluid motor for controlling said fuel device operable by fluid under pressure to adjust said fuel device to provide fuel to said engine in proportion to the pressure of the operating fluid and to provide for idling of said engine when the motor is void of fluid under pressure, means for varying the pressure of fluid in said fuel device control motor, and a valve device controlling communication between the last named means and said fuel supply motor controlled by pressure of fluid in said pipe and operative upon supply of fluid under pressure to said clutch control pipe to open said communication and upon venting of fluid under pressure from said pipe to close said communication and to vent fluid under pressure from said fuel supply motor to thereby effect idling adjustment of said fuel device.

20. An arrangement for controlling a clutch between an internal combustion engine and a propeller shaft which clutch has a neutral position, a forward position, and a reverse position, and for controlling the adjustment for a fuel device controlling the supply of fuel to said engine, said arrangement comprising in combination, a fluid controlled clutch motor for adjusting said clutch, said motor having a neutral position for neutralizing said clutch and being movable from said neutral position to a forward position upon supply of fluid under pressure to one control pipe for moving said clutch to its forward position and being movable from said forward position to said neutral position upon release of fluid under pressure from said control pipe, said motor being movable upon supply of fluid under pressure to a second control pipe to a reverse position to effect movement of said clutch from said neutral position to said reverse position and upon release of fluid under pressure from said second control pipe to effect movement of said clutch from said reverse position to said neutral position, means operable to supply fluid under pressure to and vent fluid under pressure from said first control pipe while maintaining said second control pipe open to the atmosphere and operable to supply fluid under pressure to said second control pipe and release fluid under pressure therefrom while maintaining said first control pipe open to the atmosphere, a fluid control motor for said fuel device operable by fluid under pressure to adjust said fuel device to provide fuel to said engine in proportion to the pressure of the operating fluid and operable when void of fluid under pressure, to provide for idling of said engine, means for varying the pressure of fluid in said fuel device control motor, a valve device controlling communication between the last named means and said fuel device control motor and arranged to be operated by fluid under pressure to open said communication and upon the venting of such fluid pressure to close said communication and to vent fluid under pressure from

said fuel device control motor to effect idling of said engine, and means including a double check valve device connecting the last named valve device to both of said control pipes, said double check valve device being operative upon supply of fluid under pressure to either one or the other of said control pipes to establish communication therebetween and the last named valve device and to close communication between the last named valve device and the control pipe which is open to atmosphere.

21. A control system for a boat having above deck a control station and below deck an engine room containing an engine for propelling the boat and a clutch for rendering the engine either effective or ineffective, said control system comprising in the engine room a fluid motor for moving the clutch to either its effective position or its ineffective position, an engineer's control valve in the engine room operative by the engineer for controlling said fluid motor, a pilot's control valve located at said control station above deck operative by the pilot for controlling said motor, and a selector valve located in said engine room for operation by the engineer to one position to render said pilot's control valve effective and said engineer's control valve ineffective, said selector valve being operable by the engineer to another position to render the pilot's control valve ineffective and the engineer's control valve effective.

22. An arrangement for controlling the operation of coupling means to either connect or disconnect an internal combustion engine to or from a member to be driven and for also controlling the adjustment of a fuel supply device for said engine comprising in combination, a coupling motor operable by fluid under pressure supplied to a control pipe to render said coupling means effective and upon release of fluid under pressure from said pipe to provide for rendering said coupling means ineffective, a fuel motor adjustable by fluid under pressure to adjust said fuel supply device to vary the fuel supply to said engine in proportion to the pressure of such fluid, manually operative speed control means for varying the pressure of fluid in said fuel motor and rendered effective only upon supply of fluid under pressure to said pipe and ineffective only upon release of fluid under pressure from said pipe, and coupling control means for supplying fluid under pressure to and releasing fluid under pressure from said pipe.

23. An arrangement for controlling the operation of coupling means to either connect or disconnect an internal combustion engine to or from a member to be driven and for also controlling the adjustment of a fuel supply device for said engine comprising in combination, a coupling motor operable by fluid under pressure supplied to a control pipe to render said coupling means effective and upon release of fluid under pressure from said pipe to provide for rendering said coupling means ineffective, a fuel motor adjustable by fluid under pressure to adjust said fuel supply device to vary the fuel supply to said engine in proportion to the pressure of such fluid, coupling control means for supplying fluid under pressure to and releasing fluid under pressure from said pipe, and speed control means for varying the pressure of fluid in said fuel motor rendered effective only upon operation of said coupling control means to supply fluid under pressure to said pipe and ineffective upon operation of said coupling con-

trol means to release fluid under pressure from said pipe.

24. In combination, two devices to be operated, one fluid pressure controlled means for controlling one of said devices, another fluid pressure controlled means for controlling the other of said devices, a fluid pressure supply pipe, manual control means operable to either supply fluid under pressure from said pipe to said one fluid pressure controlled means or to release fluid under pressure from said one fluid pressure controlled means for controlling the operation thereof, another manual control means operable to either supply fluid under pressure from said pipe to said other fluid pressure controlled means or to release fluid under pressure from said other fluid pressure controlled means to control operation thereof, means manually operative to either supply fluid under pressure to said pipe or to cut off the supply of fluid under pressure to said pipe, and means for actuating said devices manually.

ROY R. STEVENS.
